DESIGN FOR A HANDBAG

Irving Pichel, New York, N. Y.

Application July 9, 1941, Serial No. 101,981

Term of patent 3½ years

To all whom it may concern:

Be it known that I, Irving Pichel, a citizen of the United States of America, residing in New York city, county of New York, and State of New York, have invented a new, original, and ornamental Design for a Handbag, of which the following is a specification, reference being had to the accompanying drawing, forming part thereof.

Fig. 1 is a side elevational view of a handbag showing my new design.

Fig. 2 is a top plan view.

Fig. 3 is a perspective view showing the handbag in open position.

Fig. 4 is an end elevational view thereof.

I claim:

The ornamental design for a handbag, substantially as shown.

IRVING PICHEL.
